UNITED STATES PATENT OFFICE.

ISAAC B. KLEINERT, OF NEW YORK, N. Y.

DRESS-SHIELD.

SPECIFICATION forming part of Letters Patent No. 257,497, dated May 9, 1882.

Application filed January 19, 1882. (No model.)

To all whom it may concern:

Be it known that I, ISAAC B. KLEINERT, of New York, in the county of New York and State of New York, have invented certain new and useful Improvements in Dress-Shields; and I do hereby declare the following to be a full, clear, and exact description of the invention, such as will enable others skilled in the art to which it pertains to make and use the same.

My invention relates to an improvement in dress-shields intended to be worn in the arm-pits to protect the dress and sleeve under the arms from being soiled or discolored by perspiration; and the objects of my invention are to provide such a shield which will be impervious to moisture, and which will be of such form as to fit and protect the seam of the dress at the armpit, and also provided with an attachment whereby it may be readily secured at different points to the seams or lining of the dress without puncturing or otherwise injuring the water-proof material.

With these ends in view my invention consists in certain features of construction and arrangements of parts, as will hereinafter be described, and pointed out in the claims.

In the accompanying drawings, Figure 1 is a view in side elevation of one form of dress-shield constructed in accordance with my invention. Fig. 2 is a transverse section. Fig. 3 shows detached views of the two parts of the shield. Fig. 4 is a view in side elevation of a modification, and Fig. 5 is a transverse section of the same.

A A' represent the two flaps or parts of the shield proper, which are made of any suitable waterproofing material, such as oiled silk, rubber cloth, gutta-percha webbing, or other material. The flaps A A' are sewed together and their seam covered by a saddle-strip, B, located on the upper or under side; or two such strips may be used, one on the upper and one on the under surface. The strip B is secured in place by a double row of stitches, a a, located near its opposite edges, so that a channel or opening, b, is formed between the two flaps, near their upper edges. The object of providing this space or channel b is to cause the shield to fit over the seam of the dress at the arm-pit without puckering or drawing, and thus

render the attachment not only comfortable to the wearer, but also to prevent the tearing and rapid destruction of the shield itself. The saddle-strip B not only imparts the desired form to the shield at that point where it rests upon the seam of the dress, but it also re-enforces the shield at the point where it is subjected to the greatest wear and strain. The strip B may be secured in place by rubber cement instead of being stitched to the shield. The opposite ends of the saddle-strip B extend beyond the ends of the shield, forming attaching ends c c', which are sewed to the seam of the dress or lining at the armhole, and thus prevent the rotary displacement of the shield.

C is a supplemental shield, made of soft woolen flannel or any other soft and absorbing material, its ends being attached to the saddle-strip B.

To the central portion of the supplemental shield C is secured the attaching-band D, the ends d d' of which are designed to be attached to the seam or lining of the sleeve and seam or lining of the dress, and thus prevent the shield from vertical displacement. This method of securing the shield against displacement is a radical improvement on the prior state of the art, as formerly the shields were stitched at different points directly to the lining or seams of the dress. In this case the stitches were necessarily made near the edge or binding, so as not to puncture the waterproofing material, and by reason of such a narrow holding-surface for the stitches they would soon tear out. In my improvement the strain on the shield is practically obviated by securing it in place by means of the attaching-bands, which may be firmly stitched to the seam or lining of the dress. The supplemental shield serves to absorb the moisture or perspiration and prevent the dress from being injured by discoloration therefrom. In Figs. 4 and 5 I have illustrated the shield with the supplemental shield dispensed with. In this form of construction the side attaching-bands are secured to the saddle-strip B, and may be secured near the lower edges of the flaps or parts A A'.

While I have represented the flaps A A' as being made of waterproofing material of a single thickness, they may be made of two or

more thicknesses each; or each flap may be made of any suitable waterproofing material, and a separate cloth or absorbent lining attached thereto at its edges by seams or by 5 cement.

The saddle-strip B may be made of cotton, silk, or other fabric; or it may be made of any waterproofing fabric.

Having fully described my invention, what 10 I claim as new, and desire to secure by Letters Patent, is—

1. A dress-shield having a saddle-strip secured over the seam connecting the two flaps by parallel seams located at the opposite edges 15 of the saddle-strip, and uniting the latter to the flaps and forming an open space between their concave edges, substantially as set forth.

2. A dress-shield provided with a saddle-strip over the seam that joins the two flaps of 20 the shield, said strip extending beyond the ends of the shield to form attachments for

sewing to the dress-seams, substantially as set forth.

3. A dress-shield provided with a saddle-strip for imparting the desired form to the 25 juncture of the two flaps, and for constituting attachments to be sewed to the dress, and with side bands secured to the saddle-strip and flaps, and extending below the latter, substantially as set forth.

4. In a dress-shield, the combination, with 30 the water-proof flaps provided with a saddle-strip, as described, of a supplemental shield of absorbent material, substantially as set forth.

In testimony whereof I have signed this 35 specification in the presence of two subscribing witnesses.

ISAAC B. KLEINERT.
